BOBBIN HOLDER

Joseph E. Blanchard, Millbury, Mass., assignor to Watson-Williams Manufacturing Company, Millbury, Mass., a corporation of Massachusetts

Application May 26, 1941, Serial No. 395,226

4 Claims. (Cl. 139—207)

This invention relates to shuttles used in automatic weft replenishing looms and relates more particularly to the means for gripping and holding a bobbin in such a shuttle.

Such holding means commonly comprises a series of rings on the bobbin butt and a bobbin-holding spring having a pair of spaced resilient jaws which grip the rings on the bobbin butt when a fresh bobbin is transferred to a shuttle. Such bobbin-holding springs are subject to rather rough treatment during transfer and are difficult to firmly secure in the shuttle body.

It is the general object of my invention to provide improved means for securing a bobbin-holding spring in a shuttle. A further object is to provide means for firmly seating a bobbin-holding spring on an underlying bobbin guide-plate.

My invention further relates to arrangements and combinations of parts which will be herein-after described and more particularly pointed out in the appended claims.

A preferred form of the invention is shown in the drawing, in which

Fig. 1 is a partial plan view of a shuttle having my invention embodied therein;

Fig. 2 is a sectional side elevation, taken along the line 2—2 in Fig. 1 but with the bobbin omitted;

Fig. 3 is a side elevation of certain parts forming my improved bobbin holder, shown in spaced relation;

Fig. 4 is a plan view of a bobbin guide-plate;

Fig. 5 is a plan view of a bobbin-holding spring; and

Fig. 6 is a transverse sectional elevation, taken along the line 6—6 in Fig. 1.

Referring to the drawing, I have shown a shuttle S having a bobbin B mounted therein. The butt 10 of the bobbin B is provided with a plurality of rings 11 adapted to be received and gripped in recesses 12 (Fig. 2) in the inner faces of the spaced resilient jaws 14 of a U-shaped bobbin-holding spring 15.

The end portion of the shuttle S is recessed at 20 (Fig. 6) to snugly receive the closed end portion 21 of the spring 15, and the spring is provided with holes 22 to receive the usual holding screw 23, which is threaded into a nut 24 firmly seated in the side of the shuttle.

The parts thus far described are of the usual commercial construction, as is the bobbin guide 30 shown in Figs. 3 and 4 and having a bottom plate 31, a top plate 32 and an inclined guiding portion 33. This bobbin guide 30 is provided

with a special hole 34 in the bottom plate 31 and with a special slot 35 in the top plate 32.

The narrowed or left-hand portion of the bottom plate 31 is received in longitudinal slots 40 (Figs. 2 and 6) at the sides of the recess 20 in the shuttle S, and the narrowed or left-hand portion of the top plate 32 is similarly received in longitudinal slots 42 in the shuttle.

My improved means for firmly securing the bobbin-holding spring 15 in the shuttle S and for firmly seating the spring on the bottom plate 31 of the bobbin guide 30 comprises a screw-eye 44, a nut 45, and a lock washer 46. After the parts are assembled in the shuttle, the nut 45 is tightened on the threaded lower portion 44a of the screw-eye 44 by means of a split screwdriver or other convenient tool. The screw-eye 44 encircles the holding screw 23, which latter extends through the holes 22 in the spring 15.

Consequently, as the nut 45 is tightened, a downward force is exerted through the screw-eye 44 and screw 23 on the spring 15, and the lower edge of the spring 15 is firmly seated against the upper face of the bottom plate 31 of the bobbin guide 30.

Relative vertical movement between the spring and the bottom plate is thus effectively prevented and cutting of the spring into the bottom plate, due to lost motion between the parts, is effectively avoided.

In assembling the bobbin holder in the shuttle, the spring 15 and bobbin guide 30 are first assembled as shown in Fig. 3, and these parts are then inserted in the shuttle S, assuming the position shown in Figs. 1, 2 and 6. The screw-eye 44 is then inserted through the slot 35, and the threaded lower portion 44a thereof is guided through the hole 34 in the bottom plate 31. The slot 35 in the top plate 32 is necessary to permit assembly of these parts.

The screw 23 is then inserted through the side wall of the shuttle, the screw-eye 44 being positioned to receive the screw 23 as it is thus inserted. The lock washer 46 and nut 45 are then placed in the position shown in Fig. 6, and the nut 45 is tightened to firmly seat the spring 15 on the bottom portion 31.

The screw 23 is then tightened in the nut 24 and the bobbin holder is then fully assembled and firmly secured in the shuttle.

It will be noted that the spring washer 46 directly abuts the under side of the bottom plate 31, so that there is no interposed wood which might shrink and allow the parts to loosen. Consequently, the spring 15 will be held firmly seated

on the plate 31 during an extended period of use.

Having thus described my invention and the advantages thereof, I do not wish to be limited to the details herein disclosed, otherwise than as set forth in the claims, but what I claim is:

1. In a shuttle having a bobbin-holding spring and a bobbin guide therefor having a bottom plate underlying said spring, in combination, a clamping screw extending transversely through the shuttle body and through the shank of the bobbin-holding spring, a device positioned between the spaced sides of the spring in the shank portion thereof and engaging and directly coacting with said clamping screw, and means to draw 13 said device and clamping screw downward and to thereby firmly seat said spring on said bottom plate.

2. In a shuttle having a bobbin-holding spring and a bobbin guide therefor having a bottom 20 plate underlying said spring, in combination, a clamping screw extending transversely through the shuttle body and through the shank of the bobbin-holding spring, a screw-eye positioned between the spaced sides of the spring in the shank portion thereof and encircling said clamping screw and extending downward through the bottom plate of said bobbin guide, and means to draw said screw-eye downward and to thereby firmly seat said spring on said bottom plate. 25

3. In a shuttle having a bobbin holding spring

and a bobbin guide therefor having a bottom plate underlying said spring, in combination, a clamping screw extending transversely through the shuttle body and through the shank of the bobbin-holding spring, a screw-eye positioned between the spaced sides of the spring in the shank portion thereof and encircling said clamping screw and extending downward through the bottom plate of said bobbin guide, and means to draw said screw-eye downward and to thereby firmly seat said spring on said bottom plate, said latter means directly abutting the under side of said bottom plate.

4. In a shuttle having a bobbin-holding spring and a bobbin-guide therefor having a bottom plate underlying said spring, in combination, a clamping screw extending transversely through the shuttle body and through the shank of the bobbin-holding spring, a screw-eye positioned between the spaced sides of the spring in the shank portion thereof and encircling said clamping screw and extending downward through the bottom plate of said bobbin guide, and means to draw said screw-eye downward and to thereby firmly seat said spring on said bottom plate, said latter means comprising a nut and a lock washer inserted in the shuttle body from the bottom surface thereof and said washer directly abutting the under side of the bottom plate.

JOSEPH E. BLANCHARD.
